ROBERT PFÄFFLE, OF SCHWENNINGEN-ON-THE-NECKAR, GERMANY.

PEDESTAL LAMP.

Application filed February 12, 1928, Serial No. 87,904, and in Germany October 22, 1924.

This invention relates to a pedestal lamp for electric lights which, for transport, can be easily taken to pieces and put together again at the place of use, the lamp shade being movable to such an extent that it can be adjusted into any desired position at any point of a semispherical surface the radius of which is equal to the length of the arm of the lamp, the wire strand guide inside 10 the elements of the lamp being not damaged by this adjusting.

The lamp according to the invention is composed of three main parts screw-connected with one another, e. g. the lamp foot, 15 the lamp arm and the lamp shade said lamp shade being also composed of several pieces so that the glass insertion in the same can be well packed.

The greatest possible movability and adjustability of the lamp is obtained by mounting the lamp arm rotatably in the lamp foot, the rotation being limited to 180° by means of two stops in order to prevent the wrenching off of the wire strand; by 25 the use of a flexible tube as lamp arm which is adapted to be bent over in forward or backward direction and can be moved along the two semi-circles limited by the stops; by the use of a box-shaped connection-piece 30 between the lamp arm and the shade holder, said connection piece having a lid which might be unscrewed in order to facilitate the insertion of the wire strand; by the pivotable mounting of the lamp shade in the 35 direction of its longitudinal axis in its holder; and finally by the twisting of the flexible metal tube.

An embodiment of the invention is shown, by way of example, in the accompanying 40 drawings which illustrate the improved adjustable electric lamp.

Fig. 1. shows the improved pedestal lamp in elevation.

Fig. 2. is a longitudinal section through 45 the bearing of the lamp arm showing the stops and the screw connection.

Figs. 3 and 4 show in cross section respectively in plan view the disk mounted on the lamp foot and the stops on the same.

Fig. 5 shows the lamp foot mounted on an adjustable clamp.

Fig. 6 shows in side elevation the lamp arm with open box-shaped shade.

Fig. 7 shows in side elevation the lamp 55 arm with a closed box-shaped shade.

Fig. 8 is a longitudinal section through

the screw connection for the shade which is composed of several parts.

The lamp arm 2 made of a flexible metal tube is pivotally mounted in the cast iron foot 1 and holds by means of a box shaped connecting piece 3 the holder 4 carrying the lamp socket 5 with incandescent lamp 6 and the lamp shade 7. In a groove in the lower surface of the foot 1, a ring 8 of rubber, 60 fibres or the like is inserted to prevent scratching of the table when the lamp is moved on the same. The cast iron lamp foot 1 is covered with a metal rosette 9. A switch 10 is mounted in the lamp foot, the 65 press knob or handle of which projects from the outer surface of the foot.

Between the upper surface of the lamp foot 1 and the rosette 9 a disk 12 is inserted which has two downwardly directed studs 75 engaging with corresponding cavities in the lamp foot 1 so that the disk is prevented from rotating, the disk 12 having further two upwardly directed studs 14 which serve as stops for the nipple 15 at the lower end 80 of the lamp arm 2, said nipple having a horizontal abutment pin 16. The stop 14 and the abutment pin 16 are covered by a metal plate 17, and the lamp arm 2 and its nipple 15 are fixed in the lamp foot by 85 means of a nut 18 in such a manner that, if the lamp arm is bent down on the front side of the lamp foot 1, it can rotate in the semi-circle limited by the stops 14, and if it is bent backward it can rotate in a similar 90 semicircle on the rear side of the lamp foot limited by said stops 14 e. g. in all in a full circle around the lamp foot.

The lamp arm 2 might be mounted in a similar manner in a clamp 19 in which case 95 the nipple 15 is screwed into the clamp so that the lamp arm 2 rotates in the nipple, the rotation being limited to 180° by two stops 20 mounted in said clamp 19.

If the lamp has to be packed for transport 100 the screw connection can be easily unscrewed.

The box-shaped connection piece 3 serving to connect the lamp arm 2 with the holder 4 for the lamp shade has a screw lid 21 so that a wire strand 33 can be easily inserted. 105 Owing to this arrangement it is possible, in combination with the limiting of the rotating movement of the lamp arm 2, to conduct the wire strands 33, notwithstanding the great movability of the lamp arm 2, from 110 foot 1, across switch 10, through the lamp arm 2, the connecting piece 3, the shade

holder 4 to the lamp socket 5 so that it is invisible and inviolable.

The lamp shade 7 is made of metal, veneer or glass and has the parabolic shape of a box-shaped shade open at the lower end or of a closed shade the upper portion 7^a of which is made of green glass or opaque material, the lower portion 7^b being made of dull glass. These insertions for the shade 10 are carried by two end walls 22, 23 rotatably mounted on the arms of the shade holder and having grooves 24 and ridges 25 into which the side edges of the insertion pieces are inserted. The end wall 22 is fixed on 15 the holder 4 between the lamp socket 5 and a nut 26, the other end wall 23 being adjustably mounted on a threaded extension 27 of the shade holder by means of a nut 28, which can be fixed in its position by means 20 of a nut 28, which can be fixed in its position by means of a screw 29 a screw 30 serving for adjusting said end wall 23 in accordance with the length of the insertion 7 which insertion after the loosening of nut 28 can be 25 easily removed.

I claim:—

1. A pedestal electric lamp, comprising in combination a lamp foot, a switch in said lamp foot, a disk on the top end of said lamp foot, two stops on said disk, a lamp arm made of a flexible metal tube, a nipple on the lower end of said lamp arm and inserted into the top end of said lamp foot and traversing said disk, a horizontal abutment pin in said nipple so that said nipple and with it said lamp arm can be rotated in said lamp foot between said stops of said disk along a semi-circle on the front side of

said lamp foot and along a semi-circle on the rear side of said lamp foot after said lamp 40 has been bent to make the said abutment pin engage between said stops from the rear side, a connecting piece on the top end of said lamp arm, a holder in said connecting piece, a lamp in said holder, and a lamp shade rotatably mounted in said holder so that this lamp shade can be adjusted into any desired position.

2. A pedestal electric lamp, comprising in combination a lamp foot, a switch in said lamp foot, a disk on the top end of said lamp foot, two stops on said disk, a lamp arm made of a flexible metal tube, a nipple on the lower end of said lamp arm and inserted into the top end of said lamp foot and traversing said disk, a horizontal abutment pin in said nipple so that said nipple and with it said lamp arm can be rotated in said lamp foot between said stops of said disk along a semi-circle on the front side of 60 said lamp foot and along a semi-circle on the rear side of said lamp foot after said lamp arm has been bent to make the said abutment pin engage between said stops from the rear side, a connecting piece on the 65 top end of said lamp arm, a holder in said connecting piece a lamp in said holder, a screw lid on said connecting piece to facilitate insertion of a wire strand through the said foot, switch and connecting piece into 70 said holder, and a lamp shade rotatably mounted in said holder so that this lamp shade can be adjusted into any desired position.

In testimony whereof I affix my signature.

ROBERT PFÄFFLE.
